UNITED STATES PATENT OFFICE.

LEWIS R. WALLACE, OF WALTHAM, MASSACHUSETTS.

AUTOMATIC TRAIN-STOP MECHANISM.

Application filed June 2, 1920. Serial No. 385,922.

To all whom it may concern:

Be it known that I, LEWIS R. WALLACE, a citizen of the United States, residing at Waltham, county of Middlesex, Commonwealth of Massachusetts, have invented certain new and useful Improvements in Automatic Train-Stop Mechanism, of which the following is a specification.

This invention relates to the track box equipment, so called, in a control system for railroad trains or the like. The track box equipment or corresponding mechanism usually controls the position of an arm or other obstacle which has an interfering and a non-interfering position through which the brake setting mechanism is sprung when it is brought in contact by a moving train.

Various equipment for this part of the system has been devised, including my earlier application of June 3, 1915, Serial No. 31,932 in which a box of this general type is shown. In my present track box as in my earlier device it will be noted that the tripping obstacle which is to be interposed in the path of the tripper carried by the train is usually an arm counterweighted so that upon its release the weight raises the arm to an interfering position, while in non-interfering position the weight is supported usually by an electro-magnetic catch controlled through track or signal circuits or both.

The resetting of this counterweighted arm is preferably effected through an electric motor, so that when the block is cleared the tripping arm is reset to non-interfering position through the raising of the weight by the motor.

One of the features of great importance in all train control apparatus as heretofore explained by me in previous applications has been the construction of parts so that breakage in any single part tends to bring the device to controlling position. In case of track box equipment or the like the structure should have a collapsing tendency upon breakage or otherwise in the direction of safety, i. e., in the direction of interfering position for the tripping arm.

It is furthermore necessary to provide for operating movements effective regardless of any variation in position, wherever the apparatus may have been stopped in phase of its last operation, so as to take up any lost motion in order that each actuating impulse

may effect a complete operation of the parts.

It will be understood that all the operating mechanism with the exception of the track trip which is necessarily exposed for actuation by the train-carried trip, is enclosed in a locked housing. In order to prevent unauthorized tampering with the system I provide a novel electro-magnetic latching mechanism, so constructed and arranged as to be incapable of release except by actual de-energization of the electro-magnets.

The construction is such that even though the track trip be grasped in an effort to lift it into interfering position, such movement would be impossible owing to the positive lock. In the other aspect, the construction is such that with the track trip set at interfering position it is impossible to force the trip to non-interfering position even if extraordinary pressure, as for example standing on the raised trip, be brought to bear on the trip.

These and other difficulties I have overcome by means which may be variously embodied in such structures and which I have combined in novel and practical form, all as will be more fully hereinafter set forth.

In the drawings I have shown for the purpose of illustration of my invention a track box equipment found well adapted to practical use in railroad operation and which shows the principles of my invention involved in this case.

Throughout specification and drawings like reference numerals are employed to indicate corresponding parts, and in the drawings:

Fig. 1 is a plan view of my box with cover removed.

Fig. 2 is a side sectional view exposing the interior equipment.

Fig. 3 is a similar view showing the parts in trip position.

Fig. 4 is a diagrammatic view of the wiring.

Fig. 5 is a sectional detailed view of an electric cut-out mechanism which operates, when the trip arm shaft is removed for any cause, to cause the track box in railroad block next preceding to assume trip or danger position.

Fig. 6 is a section on the line $x-x$ Fig. 3, and

Fig. 7 is an end view looking from the

right towards the left in Fig. 3 with the end of the box cut away to expose the interior.

The equipment is housed in a box or casing 1 adapted to be closed by a suitable cover 5 (not shown), and having suitable bearings 2 in which is journaled a transverse shaft 3 having formed integrally on the end thereof an arm 4 which constitutes a track obstacle or tripping device on the air brake release 10 of the train.

Fast on the shaft 3, see Figs. 2 and 3, is a weight member 6 which is supported through latches 7 engaged by spring sustained hooks 7¹. The latches are formed as 15 two lateral projections on the outer faces of the two arms of the latch fork 8 which itself straddles the disc 55. The latch fork 8 is pivoted at 9 on one face of the weight 6 and normally sustained by a toggle connection 10 and held distended by a catch lever 12 having 20 a notch 12¹ which is normally hooked under an opposing catch on the armature 13. This constitutes the locking system for holding the weight raised and the arm 4 depressed in non-interfering position.

In order to avoid tampering I provide a 25 second locking system adapted to hold the arm against unauthorized movement away from interfering position. This lock consists of an arm 14 rocking on a pivot 15 and counterweighted at 16 so as normally to be tipped up as shown in Fig. 2, so that it will engage the spur 6¹ of the counterweight 6 on the shaft of the trip arm.

The trip arm is reset through a motor 35 driven restoring device which raises the counterweight 6 of the trip arm and also at a suitable phase of the resetting motion raises the counterweight 16, so as to clear 40 the stop 14 in the path of the weight while it is being raised.

It is to be understood at the outset that the tendency of both the counterweight of the tripping arm and the counterweight of the stop 14 is towards safety i. e., away from a position to interfere with the movement of the parts to set the device in operative position.

The restoring mechanism consists of a 50 disk 55 journaled at 56 within the casing and carrying a weight lifting roll on both faces mounted on the stud 17 and on one face a pin 18 adapted to be disposed so as to engage the notch 16¹ on the counterweight 16 of the stop 14 and move that stop out of engaging position just as the rolls 17 begin to pick up the counterweight 6.

The disk 55 is driven through a gear 19 driven by a pinion 20 turned by a drive 21 60 on the shaft of the motor 22.

There are two different circuit closers in the system which will be next described. These are first the simple switch construction 70 which opens or closes the shunt circuit

which is cut in on the main battery circuit 65 from the next block and is operated by the stops 60 and 61 on the counterweight 6; and the second a safety circuit breaker 30 which is cut in on one line of the track circuit and normally held closed by the shaft 3 of the 70 tripping arm 4 when properly set in its bearings, but releasable in case the shaft 3 is broken or removed from its bearings, either maliciously or for the purpose of repair.

The effect of the circuit breaker 30 is to 75 set the trip arm of the box on the preceding section against an oncoming train. The preferred construction of these two devices will be further described later on.

The circuit controlling the electro-magnets 80 11 consists of a lead wire 120 (see Fig. 4) from the binding post of one magnet, one pole at the track battery B and the lead wire 121 on the opposite pole of said battery and the binding post of the other magnet 85 of the pair. This is normally a closed circuit. The locking circuit 120-121 is included in the dominant circuit of the block signal system in any desired manner, as by 90 relay R.

When the locking circuit is closed and the magnets 11 energized, the latch 7 is held against collapse by the holding toggle 10 through the catch lever 12 which is hooked on the armature 13 held to the face 95 of the poles of the energized magnets. When thus held, the counterweight 6 is supported by the latch 7 on the hook 7¹.

When the circuit 120-121 is broken, the de-energized magnets 11 release the armature 13, permitting the collapse of the toggle 10 and the dropping of the weight 6 which raises the trip arm 4 to interfering position. Shunted in on the circuit 120-121 is the 100 motor circuit 50-51 in which the switch 105 or circuit breaker 70 is interposed.

When the circuit 120-121 is restored after a train has left the block, the current is given to the motor 22 through the circuit breaker 70 which had been closed by the 110 contact of the adjustable lug 60 on the counterweight 6 when it had dropped.

This circuit breaker 70 is again opened and the motor circuit broken by an opposite adjustable lug 61 on the weight 6 as 115 will be hereinafter described.

The circuit breaker 30 is shown in place in Fig. 1 and in detail in Fig. 5. This device may conveniently be formed as a gravity operating arm 31 pivoted at 32 in suitable ears 33 formed on a housing 34 which is secured in any convenient manner within the track box housing as by screws 35 seating in suitable lugs 36 cast on the inside of the track box (see Fig. 5). The free end 120 of the arm 31 is normally disposed under and against the sleeve surrounding the rock shaft 3 and remains in such position as long

as the rock shaft, trip arm and counter-weight are in their proper positions. When the weight or attached parts are removed, either maliciously or for legitimate purposes of repair or replacement, the free end of this arm will automatically rock upwardly, and in its movement will automatically set the trip arm of the preceding track box at danger in order to guard against rear-end collision.

For this purpose the opposite end of the arm 31 is pinned at 37 to the upper end of a movable contact 38 which has suitably guided travel in the housing 34, and carries a contact finger 39 adapted to normally bear against the inner ends of a pair of fixed contacts 39¹, set one on each side of the movable contact 38, and from which extend the lead wires 81 connecting the circuit breaker 30 with the track circuit governing the preceding box.

In the normal position of the parts, the circuit is closed through the contacts 39 and 39¹, but when for any reason the free end of the arm 31 is released, the contact finger 39 drops, destroying the electrical contact between the binding posts of the wires 81 and breaking the track circuit to the electro-magnetic latch in the track box of the preceding block, and allowing the trip arm of said box to automatically assume danger position.

Tracing the operations from the position shown in Fig. 2 in which the tripper arm is held in non-interfering position, the block being clear, we will presume that a train has passed the track box and entering the block ahead is required to be protected in the rear.

As soon as the train enters the block the track circuit is broken and the current which has been maintaining the magnets 11 in an energized state being taken away, releases the armature 13 which permits the collapse of the toggle 10 so that the bar 7 escapes from its supporting hooks 7¹ and the weight 6 falls to the position indicated in Fig. 3.

In falling, the weight turns the shaft 3 and raises the arm 4 to interfering position, in which position it is locked by the arm 14 which is temporarily tipped up in passing by the fall of the counterweight 6 but which immediately assumes normal locking position preventing the arm 4 from being forced down accidentally or maliciously. The arm therefore stands in interfering position, so that the air brake system of a following train will be tripped and the brake set for the protection of the preceding train in the next block ahead.

When however the block ahead is cleared so that the line circuit is again unbroken, the trip arm will be restored through the following operations. The weight 6 in fall-

ing brings the adjustable lug 60 in contact with the slide bar 41 of a circuit closer 70. The circuit closer 70 has an insulated section 42 upon which bear a pair of brushes 43 attached to the binding post 44.

The thrust of the lug 60 against the bar 41 rotates the circuit closer 70, bringing the brushes into contact closing position and completing the shunt line circuit 50-51 through their binding post 44-44¹. This gives to the motor 22 the line current which starts it in rotation and through the pinion 22, and the gear 19 rotates the disk 55 until its rollers 17 comes in contact with the under faces of the latch fork 8 on the weight 6 which is raised until restored to its position as shown in Fig. 2, when the stop 61 again shifts the bar 41 to rotate the circuit breaker 70 and breaks the motor circuit 50-51.

Just before the rolls 17 engage the latch fork 8 and begin lifting the weight 6, the pin 18 trips the counterweight 16 by engagement with the shoulder 16¹ pushing the arm 14 down out of the way. There is sufficient dwell in the engagement of the pin 18 with the counterweight 16 to give the rolls 17 time to lift the toe 6¹ of the weight 6 clear of the end of the arm 14 which of course is raised by the falling of the counterweight 16 as soon as it is released from the pin 18¹.

The toggle 10 which is collapsed on the falling of the weight as indicated by the broken lines in Fig. 2 immediately straightens itself out by gravity assisted by the action of springs 10¹ as soon as it is released from its strain in supporting the weight 6 so that it is immediately in position to be re-engaged by the hook 7¹ whenever the weight is restored by the motor.

It will therefore be seen that in a comparatively simple structure in accordance with my invention there is embodied full provision not only for the setting actuation and resetting of a safety tripper, but one guarded against accident or tampering, and all so constructed and disposed as to tend towards an actuation for safety if any internal part breaks or gives away.

Various modifications may of course be made in the details of structure and design, and in the arrangements of parts, all without departing from the spirit of my invention if within the limits of the appended claims.

What I therefore claim and desire to secure by Letters Patent is:

1. In automatic train stop apparatus, the combination with a track obstacle and a gravity operating member therefor, of a lock for said gravity member when in raised position and a lock for said member when in lowered position.

2. In automatic train stop apparatus, the

- combination with a track obstacle and a gravity operating member therefor, of a lock for said gravity member when in raised position and a lock for said member when in lowered position, both locks having a releasing action in the direction of the safety position of the apparatus.
3. In automatic train stop apparatus, the combination with a track obstacle and a gravity operating member therefor, of an electro-mechanical lock for said gravity member when in raised position and a mechanical lock for said member when in lowered position, both locks having a releasing action in the direction of the safety position of the apparatus, and said mechanical latch automatically applied and released by the movement of the gravity member from one to the other of its positions.
4. In automatic train stop mechanism, in combination with a block signal system, a track obstacle in each block, a gravity operating member therefor, a lock normally maintaining said track obstacle in safety position, and a supplementary lock permitting the track obstacle in the block behind to assume danger position in the event of removal of the gravity member from the track obstacle in the immediately preceding block.
5. In automatic train stop mechanism, in combination with a block signal system, a track obstacle in each block, a gravity operating member therefor, a lock normally maintaining said track obstacle in safety position, and a supplementary lock permitting the track obstacle in the block behind to assume danger position in the event of removal of the gravity member from the track obstacle in the immediately preceding block, and comprising an arm normally disposed in movement-arresting relation to said track obstacle in the immediately preceding block and an electro-magnetic latch for said arm.
6. In automatic train stop mechanism, in combination with a block signal system, a track obstacle in each block, a gravity operating member therefor, and a lock for said track obstacle in each block constructed and arranged to permit the track obstacle in the block behind to assume danger position in the event of removal of the gravity member.
7. In automatic train stop mechanism, a track obstacle, a counter-weight therefor, a latch pivotally mounted upon said weight, a resetting member rotatable relative to said latch, a hook normally engaging said latch, a toggle secured to said latch, an armature releasably engaging said toggle, an electro-magnet cooperative with said armature, and a weight restoring element mount-
- ed on said resetting member for elevating action upon said latch.
8. In automatic train stop mechanism, a track obstacle, a counter-weight therefor, a forked latch pivotally mounted upon said weight, a resetting member rotatable between the forks of said latch, a hook normally engaging said latch, a toggle secured to said latch, an armature releasably engaging said toggle, an electro-magnet mounted upon said weight and cooperative with said armature, and a weight restoring element mounted on said resetting member for elevating action upon said latch.
9. In automatic train stop mechanism, a track obstacle, a gravity operating member therefor, an electro-magnetic latch for locking said gravity member in raised position, a mechanical latch for locking said gravity member in lowered position including a gravity locking member normally tending toward the safety position of the apparatus, a predominant circuit in which said electro-magnetic latch is included, a resetting circuit subject to said predominant circuit, a resetting motor included in said resetting circuit, and power transmitting connections from said motor to said gravity member including a member having an element adapted for restoring action upon the gravity member and a second element adapted for tripping engagement with the mechanical latch to release said latch and permit restoration of the gravity member.
10. In automatic train stop mechanism, a track obstacle, a gravity operating member therefor, an electro-magnetic latch, mounted upon said gravity member and including a system of toggle links for locking said gravity member in raised position, a mechanical latch for locking said gravity member in lowered position, including a gravity locking member normally tending toward the safety position of the apparatus, a predominant circuit in which said electro-magnetic latch is included, a resetting circuit subject to said predominant circuit, a resetting motor included in said resetting circuit, and power transmitting connections from said motor to said gravity member, including a rotatable member having an element adapted for restoring action upon the gravity member and a second element adapted for tripping engagement with the mechanical latch to release said latch and permit restoration of the gravity member.

In testimony whereof I affix my signature in presence of two witnesses.

LEWIS R. WALLACE.
